CLAIM

The ornamental design for a clutch cover, as shown and
described.

DESCRIPTION

FIG. 1 is a perspective view of a clutch cover.

FIG. 2 is a back side view of the clutch cover.

FIG. 3 is a front side view of the clutch cover.

FIG. 4 is a right side view of the clutch cover.

FIG. 5 is a left side view of the clutch cover.

FIG. 6 is a top view of the clutch cover.

FIG. 7 is a bottom view of the clutch cover.

FIG. 8 is a perspective view of an alternative clutch cover.

FIG. 9 is a back side view of the alternative clutch cover.

FIG. 10 is a front side view of the alternative clutch cover.

FIG. 11 is a right side view of the alternative clutch cover.

FIG. 12 is a left side view of the alternative clutch cover.

FIG. 13 is a top view of the alternative clutch cover; and,

FIG. 14 is a bottom view of the alternative clutch cover.

(Continued)

The broken lines shown in FIGS. 8-13 are for the purpose of illustrating portions of the clutch cover that form no part of the claimed design.

1 Claim, 10 Drawing Sheets
